(57) **CLAIM**

The ornamental design for a surgical instrument, substantially as shown and described.

DESCRIPTION

FIG. 1 is a perspective view of a front side of an intradiscal shim showing our new design;

FIG. 2 is a perspective view of a rear side thereof; and,

FIG. 3 is a side view thereof.

The broken lines shown in the figures are included for the purpose of illustrating portions of the article and form no part of the claimed design.
